UNITED STATES PATENT OFFICE.

FRED CUSHING MOORE, OF SPOKANE, WASHINGTON.

PLATE-BOLTING-UP MACHINE.

Application filed August 29, 1924. Serial No. 734,869.

This invention relates to improvements in plate bolting-up machines and consists of the matters hereinafter described and more particularly pointed out in the appended 5 claims.

The invention relates to the type of machine by means of which plates, which are to be permanently bolted or riveted together, are drawn together and clamped at intervals 10 by key bolts or the like which hold the plates in clamped relation until the are permanently bolted or riveted together at points in the neighborhood of the key bolts, after which said key bolts are removed and are 15 replaced by permanent bolts or rivets.

Machines of the kind include an abutment member for engagement with the nearer plate of the two plates which are to be drawn together; a pull rod, movable longitudinally with reference to the abutment member and at right angles to the planes of the plates to be drawn together; an actuating element for the pull rod, which may be a pair of toggles or other suitable mechanical elements which will efficiently operate the pull rod with respect to the abutment member; a power element to drive the actuating element; a gripping member on the pull rod; a key bolt which is adapted to be inserted through rivet holes in the plates to be drawn together with its head engaged against the remote plate, the near end of said bolt being adapted to be gripped by the gripping member; and a wedge or other clamping device adapted to cooperate with the bolt to lock the plates in their contacting position after they have been drawn together by the operation of the machine.

The invention has to do with cooperating 40 members on the gripping device and the bolt and its object is to provide novel and improved features in these members which will increase the efficiency of the gripping device; will prolong the life of the bolt; and 45 will facilitate the release of the bolt by the gripping device when the machine has done its work and is ready to be moved to another position to again draw the plates together.

The many advantages of the invention 50 will appear more fully as I proceed with the specification.

In the drawings:

Figure 1 is a view representing in perspective the novel form of key bolt included 55 in the invention.

Figure 2 is a view representing a vertical

section through the parts of a plate bolting-up machine of the kind referred to, located in the immediate neighborhood of the plates, with the gripping device engaged with the 60 bolt ready to draw the plates together.

Figure 3 is a view similar to Figure 2, illustrating the plates drawn together and clamped in this position and with the gripping device released from its engagement 65 with the bolt. The plane of the section of the figure is at right angles to the plane of the section in Figure 2.

Figure 4 is a view representing a transverse section through Figure 2, the plane 70 being indicated by lines 4-4 in Figure 2.

The particular bolting-up device illustrated in the drawings is one in which the bolt, the pull rod and the gripping device are pneumatically operated as for example, 75 shown in Patent No. 1,479,712 granted January 1, 1924, to F. N. Hallett. But the invention is in no way limited to a machine of this kind which is selected for purposes of illustration only.

Referring now to that embodiment of the invention illustrated in the drawings: 10 indicates the plate-engaging end of the abutment member, the same in this case being in the form of a cylinder which is bifurcated 80 toward its bottom end to provide slots or openings 11 through which the wedge associated with the key bolt may be inserted when the plates are drawn together. 12 indicates the pull rod suitably mounted for 85 vertical reciprocation within the abutment member. 13 indicates the gripping member, 14 the key bolt and 15, 16 respectively the remote and near plate.

The key bolt has a body 17 which is preferably round and is of such diameter that it may be easily inserted through the rivet holes in the plates to be clamped together. At one end said bolt has a head 18 which is shown as, and is preferably, though not necessarily, integral with the bolt. The bolt is provided with a transverse slot 19 which is such a distance from the head that a wedge 20 may be inserted therethrough to clamp the plates together in a familiar manner after said plates have been drawn into engagement by the machine, as illustrated in Figure 3.

The end of the bolt remote from the head and beyond the slot 19 is reduced in diameter as indicated at 20^a, at a point near its end, where it is again enlarged to provide 110

an auxiliary head 21. Said head is of substantially the same diameter as the main body of the bolt 17, so that it may easily pass through the rivet holes.

5 The auxiliary head 21 is preferably rounded as shown; but the part of the head adjacent the reduced part 20 of the bolt provides a shoulder 22 to be engaged by the gripping device. Said shoulder, for a purpose that 10 will presently be made clear, is preferably made at an angle which is approximately 45 degrees, with reference to the length of the bolt.

The gripping device comprises a cylinder 15 23 with a head 24 fixed to the end of the pull rod 12 and constructed in such a manner that it will slide with the pull rod within the abutment cylinder 10. 25 indicates a piston movable in the cylinder 23 and normally held in a position adjacent to the cylinder head 24 by coiled springs 26 which act between the lower face of said piston and an annular shoulder 27 in the bottom of the cylinder. Secured to the bottom of 25 the piston 25 is a block or a plug 28 which carries clutch jaws 29 of familiar construction. Said clutch jaws are supported on the block by laterally extending pins 29^a and by oppositely acting springs 30 and 31 are caused normally to assume an open position 30 as illustrated in Figure 3. The lower, outer ends of the jaws and the inner edge of the end of the cylinder 23 are formed at an angle to the vertical in such manner as to coact 35 when the piston head 25 is moved downwardly to force the jaws inwardly to grip the end of the bolt, as in the Hallett patent hereinbefore referred to.

There are, as shown in the drawings, 40 three of the jaws 29, which are segments of a cylinder and which are so proportioned that when in the gripping relation they will be brought closely together as illustrated in Figure 4. The bottom ends of the jaws are 45 each provided with a grip 32 which projects inwardly to engage the reduced part 20 of the bolt and formed at the top at an angle substantially the same as the angle of the shoulder 22 on the bolt, namely, approximately 45 degrees.

The operation of the gripping device is as follows: The bolt is inserted through the rivet holes in the remote plate and the rivet holes in the near plate to bring it into 55 position within the abutment cylinder 10, which has been previously placed in position. The gripping device with its jaws and grips is then in the position with reference to the auxiliary head 21 of the bolt, substantially as shown in Figure 3, (but without the wedge 20 and with the bolt and plates as illustrated in Figure 2). The pneumatic fluid is then introduced through 60 the tubular pull rod 12 into the cylinder 13 of the gripping device, thus forcing the

piston 25 downwardly towards the bolt. This brings about the engagement of the jaws 29 with the inwardly inclined end of the cylinder 23 which forces the jaws inwardly to bring the grips 32 into engagement with the reduced part 20^a of the bolt below the angular shoulder 22, which forms the base of the auxiliary head 21. The device is then operated to move the pull rod 12 upwardly. This moves the gripping device also upwardly until the inclined part 32 of the grip of the jaws comes to engagement with the shoulder 22 on the bolt, whereupon in the remaining operation of the pull rod, the plates are drawn together 80 in a familiar manner. When they have been finally brought to contact, the wedge 20 is driven into the slot 19 to clamp the plates together. The pneumatic pressure against the piston 25 is then released whereupon the spring 26 forces the cylinder head up into the position shown in Figure 3, thereby permitting the lower ends of the jaws to spread apart to release the grips 32 from their engagement with the bolt in the 85 usual manner.

The jaws 29 should and in many cases do release the bolt in the manner described so that the bolting-up machine may be easily disengaged; but in other cases and particularly when the machine is operated with the abutment member and pull rod in a horizontal position, one or more of the jaws, as for example, those on the upperside of the horizontal bolt, will stick or tend to stick 90 in its engaged position, with the grip 32 engaged against the shoulder of the auxiliary head 21. As a result, difficulty in prior construction was encountered in disengaging the gripping device from the bolt. By 105 forming the shoulder 22 on the auxiliary bolt head at an angle of approximately 45 degrees and the upper engaging part of the grip 32 of the jaw at a like angle, the jaw is forced outwardly by the co-acting engagement of the grip and the inclined shoulder of the auxiliary head when the machine is pulled away from the bolt, even when it tends to stick in the position engaged with the auxiliary bolt head. Thus, 110 115 the disengagement of the jaws from the bolt is greatly facilitated.

While I have given the angle of the shoulder on the auxiliary bolt and the corresponding part on the grip as approximating 120 45 degrees, it will be understood, this is only given as the best angle and that the invention is not to be limited to that exact angle.

By means of the construction of the bolt 125 and of the grips on the gripping jaws, the life of the key bolt will be greatly lengthened since the gripping jaws will efficiently and securely grip the auxiliary head of the key bolt without any tendency to "chew" 130

or mar the end of the bolt which is gripped, which has been one of the main things to shorten the life of such bolts in apparatus of the kind heretofore used. Thus, the 5 bolts of the kind described may be used over and over again without undue wear, with the result that the expense of the use of a bolting-up machine of the kind is greatly reduced.

10 I claim as my invention:

1. In a machine of the class described the combination comprising a gripping device having gripping jaws, a bolt having a body with a head at one end, the body being reduced near the other end and having an auxiliary head at said last named end, which is of substantially the same diameter as the body, the base of said auxiliary head being formed to provide a shoulder inclined 15 at an angle less than a right angle to the length of the bolt, and the gripping jaws being provided with grips formed to engage the reduced part of the bolt body, having similarly inclined parts adapted to automatically engage with the inclined shoulder at 20 the base of said auxiliary head, and means for causing the jaws to grip the bolt.

2. In a machine of the class described the combination comprising a gripping device 25 having gripping jaws, a bolt having a body with a head at one end, the body being reduced near the other end and having an auxiliary head at said last named end,

which is of substantially the same diameter as the body, the base of said auxiliary head 35 being formed to provide a shoulder extending at an angle of substantially 45 degrees to the length of the bolt, and the gripping jaws being provided with grips formed to engage the reduced part of the bolt body, 40 having inclined parts adapted to automatically engage with the inclined shoulder at the base of said auxiliary head, and means for causing the jaws to grip the bolt.

3. A key bolt for machines of the class 45 described, consisting of a body provided with a head at one end, said body being reduced in diameter in all directions near the other end, and being provided at said last named end with an auxiliary head which is of substantially the same diameter as the body.

4. A key bolt for machines of the class described, consisting of a body having a head at one end, said body being reduced near its other end, and being provided at said last 55 named end with an auxiliary head of substantially the same diameter as the body, said auxiliary head having a base which presents a shoulder adjacent the reduced part of the bolt which extends at an angle of substantially 45 degrees to the length of the bolt.

In testimony that I claim the foregoing as my invention, I affix my signature this 23 day of August, A. D., 1924.

FRED CUSHING MOORE.
